(57) **CLAIM**

The ornamental design for computer-cord-connector, as shown and described.

DESCRIPTION

FIG. 1 is a front elevational view of computer-cord-connector showing my new design;
FIG. 2 is a rear elevational view thereof;
FIG. 3 is a left elevational view thereof;
FIG. 4 is a right elevational view thereof;
FIG. 5 is a top plan view thereof;
FIG. 6 is a bottom plan view thereof; and,
FIG. 7 is a perspective view thereof.
